CONCRETE TILE MACHINE

William M. Beyersdorfer, Glendale, Calif.

Application July 8, 1946, Serial No. 682,084

5 Claims. (Cl. 25—41)

1

This invention relates to apparatus for the automatic manufacture of structural tile from concrete.

The purpose of the invention is to provide a simple and relatively inexpensive machine for the above purpose, capable of operating at high speed without risk of crushing or breaking the product and functioning with the minimum of attention and labor.

An exemplary form of the apparatus is illustrated in the attached drawings, in which:

Fig. 1 is a side view of the complete assembly;

Fig. 2 is a plan view of the same;

Fig. 3 is an end elevation of the machine, as on the line 3—3 of Fig. 1;

Fig. 4 is a cross section, as on the line 4—4 of Fig. 1;

Fig. 5 is a side elevation of the concrete hopper 31 of Fig. 1;

Fig. 6 is a plan view of a portion of the pallet supporting mechanism, as on the line 6—6 of Fig. 3;

Fig. 7 is a side elevation of the same, as on the line 7—7 of Fig. 6;

Fig. 8 is a detail of part of the pallet feeding mechanism generally indicated at 55 in Fig. 1;

Fig. 9 is a plan view of the timing control means generally indicated at 64 in Fig. 1;

Fig. 10 is a plan view of an exemplary tile mold block, and

Fig. 11 is a longitudinal section of the same, as on the line 11—11 of Fig. 10.

It may facilitate understanding of the structure to give first a brief description of its functions. A bottomless mold block is moved over a bed plate to a position beneath a hopper from which it is filled with concrete in thickly fluent condition. Vibrations are transmitted through the bed plate to consolidate the material in the molds. The block is then moved laterally away from the hopper, an extension plate level with the upper edge of the mold following its movement to close the lower end of the hopper. At the end of this lateral movement a plunger moves downwardly to extrude the tile onto a wooden pallet, which is lowered as the tile passes out of the mold. The mold then returns to be recharged while the pallet continues its downward movement until it encounters a continuously moving conveyor belt by which it is carried away. Another pallet is then drawn into position to receive the next tile, being taken from the bottom of a stack of pallets held in a feeding rack.

Referring now to Figs. 1, 2 and 3, the framework of the apparatus consists of a base 20, posts

2

21, side members 22, extension members 23, a gallows frame 24 and a hopper frame 25. The base may desirably be welded up from tank plate, the remaining elements being of suitable structural shapes.

The upper faces of side members 22 are planed to afford a level track on which a travelling plate 26, preferably mounted on pin bearing rollers 27, is reciprocated by a piston rod 28 working in a double-acting pneumatic cylinder 29. The right hand end (as illustrated) of this plate is attached to a mold block 30 which also is carried on rollers. The mold block and the travelling plate are so positioned that their upper faces are plane and level.

A concrete hopper 31 is supported from hopper frame 25 in such manner as to be capable of vertical adjustment, as for example by the studs and pairs of nuts 32 of Fig. 5. The lower edge 20 of the hopper should barely clear the upper faces of the mold block and plate, the adjustment being such as to avoid excessive friction without incurring undue leakage. As indicated in Fig. 5, the inner faces of the hopper are flared downwardly to avoid the possibility of hanging up of the charge. Any convenient means, not shown, may be provided for keeping the hopper filled with concrete while the machine is in operation.

Immediately beneath the hopper and spaced from it by the exact thickness of the mold block is a vibrating plate 33 which is supported at its corners by cross members 34 (Fig. 4) and studs 35 and is tied down by assemblies generally indicated at 36, each of which includes a rubber dampening ring 37. The height of this plate is so adjusted that the lower edge of mold block 30 slides freely over it as the block moves into and out of filling position.

The vibrating plate is provided centrally with a means generally indicated at 38 for producing rapid vibrations of very small magnitude. This element is not shown in detail as various types of mechanical or magnetic vibrator may be used. The preference is for an electrically actuated impulse vibrator of the type known commercially as "Syntron," or a high-speed, motor-driven, unbalanced revolving weight may be substituted. In either case the adjustable wedges 39 may be used to limit the magnitude of the vibratory movement.

The gallows frame 24 is provided internally with ways 40 which position two vertically moving elements. The upper of these elements, the knockout, consists of a rigid cross member 41 guided by bearing rollers 42, this member being

raised and lowered by a pair of double acting pneumatic cylinders 43—43 acting through lugs projected from the ends of member 41. A group of plungers 44, formed to enter and pass through the openings in the mold block and attached to member 41, eject from the molds, on the down stroke, the tile formed by the filling of the molds and the consolidation of the wet concrete by vibration. This extrusion of the tile occurs at the right hand end of the movement of the mold block and after a receiving pallet has been placed beneath it as next described.

The lower elements reciprocating in the gallows frame are the pallet supports located at 45 in Fig. 3 and detailed in Figs. 6 and 7. Each of these supports consists of an L-block 45 guided by bearing rollers 46 and having a projecting lug 47. The lower bar of the L is extended laterally as at 48 and each end of this lateral extension is pierced to receive a slip rod 49 which is urged upwardly by a coil spring 50, a retaining nut 51 being placed at the lower end. The upper ends of the two rods at each side of the gallows frame are attached to a horizontal bar 52 which supports one end of the pallet. The two supports are raised or lowered simultaneously by two double acting pneumatic cylinders 53, coupled to lugs 47 as shown.

The pallet itself, indicated at 54 in Figs. 2, 3, 7 and 8, is a rectangular piece of thin wood, plywood or composition, of such dimensions as to receive the tile ejected from the molds by one stroke of the plungers. The length of this board must be such as to permit it to pass between extension members 23 when supports 45 are lowered.

The pallets are stacked in a feed rack formed by end plates 55 attached to the extension members 23 and small angles 56 attached to their sloping edges. The two angles at the forward (left) end of the rack terminate a sufficient distance above the ledges 57 on which the ends of the stack rest as to permit one pallet at a time to be drawn out beneath them.

The pallets are drawn, one at a time, from the bottom of the stack by a feeding member 58 which slides in guides, not shown, formed on the inner faces of members 23. The feeding member is attached to and moved in synchronism with the mold block by side arms 59. The bar 58 carries in pivots a light frame 60 from which lugs 61 project upwardly, these lugs being held in the elevated position by an overbalancing weight 62. As the feeder travels just below the level of ledges 57 on which the stack of pallets rests, an outward (right hand) movement of the feeder causes lugs 61 to be depressed and pass beneath the stack until they enter a pair of notches 63 formed near the rearward edge of the pallet. On a reverse (left hand) movement of the feeder the pallet is drawn onto the pallet support members 52, which at that time are close to the upper limit of their travel.

The pallet is thus brought to a position beneath the mold block, which at this time is in the extended position, and as the supports 52 reach the upper limit of their travel the pallet is lightly pressed against the lower face of the block by springs 50. Plungers 44 then travel downwardly, ejecting the formed tile from the molds, the pallet supports simultaneously moving in the same direction and at more or less the same speed. Just prior to the end of the downward movement of the supports they pass below the upper surface level of a constantly travelling conveyor belt

83, on which the pallet and its load is deposited and carried away from the machine. The supports are held in the depressed position until the pallet has cleared, after which they rise to receive another pallet.

The timing of the air supplies to the cylinders and of the electrical supply to the vibrator is controlled by mechanism generally indicated at 64 in Figs. 1 and 9. Four cams 65, 66, 67 and 68, 10 having arcuate faces of different radii, are mounted on a common shaft 69 which is driven through suitable reduction gear 70 by an electric motor 71. The gear reduction is desirably so proportioned to the motor speed as to rotate the cam shaft at about three revolutions per minute. If preferred, a variable speed motor, or speed changing gears, may be used to vary the output of the machine which, under some circumstances, can be speeded up materially beyond three cycles per minute.

The cams contact push rods 72 which are urged against their faces by open coil springs 73. The arrangement of these cams as regards the length of the shaft is immaterial and the following arrangement is by way of example only. Thus, the push rod contacting cam 65 may actuate a four-way valve 74 from which tubing connections 75 lead to opposite ends of cylinder 29. Cam 66 similarly actuates four-way valve 76 25 from which tubing connections 77 lead to opposite ends of cylinders 53, each of these connections being branched to place the two cylinders in parallel. Cam 67 actuates valve 78 from which similar branched connections lead to the 30 two ends of cylinders 43. Cam 68 opens and closes an electrical switch 80 connected by leads 35 81 with vibrator 38.

The arcuate lengths of the cam lobes and their radial positioning on the shaft, controlling the 40 order in which the valves and switch reverse, are critical as regards order though there is some leeway as regards length. The arrangement of the cam lobes is best illustrated by a recitation of the order in which movements of the three 45 reciprocating elements occur. Starting with mold block 30 in position beneath hopper 31, the sequence is as follows:

a. The mold remains stationary while it is filling by gravity and for a brief period thereafter 50 during which switch 80 is closed and the vibrator is in action;

b. With the extrusion plungers 44 fully elevated and the pallet supports 52, carrying an empty pallet, in partially elevated position, valve 74 55 admits air into the left end of cylinder 29, moving the travelling plate and mold block into contact with stop 82, the hopper being now closed by the travelling plate and the mold block being in register with the plungers. The same 60 movement causes lugs 61 to engage the notches in the lowermost pallet in feed rack 55;

c. The supports 52 continue their upward movement to bring the empty pallet up to the bottom of the mold block;

d. Valve 78 moves in a direction to admit air to the upper ends of cylinders 42, causing the plungers to eject the tile from the molds. Simultaneously valve 76 admits air to the upper ends of cylinders 53, causing the pallet supports and 70 filled pallet to move downwardly;

e. Valve 78 reverses, admitting air to the lower ends of cylinders 42 and raising the plungers free from the molds. Supports 52 continue their downward movement, depositing the filled pallet 75 on the conveyor;

f. Valve 14 reverses, admitting air to the right hand end of cylinder 29 and returning the mold to the starting position as in "a" above. This movement draws a pallet from the bottom of the stack and over the ends of flanges 51, permitting it to fall onto supports 52.

The movements above described are successive except as regards the pallet supports 52, the rate of movement of which must be exactly controlled, at least in the rising direction. Thus at the time at which the empty pallet passes over the ends of ledges 51, the supports must be above the level of conveyor belt 83 as otherwise the empty pallet will be carried away. The upward movement of the supports must not be completed until movement "c" is completed and the mold block is again in register with the ejection plungers. Consequently the rising movement of the supports occupies the larger part and the subsiding movement only a small part of the time of a complete cycle, a variation in rate for which the mere reversal of a valve does not provide. This variation in rate may be produced by throttling the air supply to the lower ends of cylinders 53, as for example by minute perforations in the discs of check valves, located as at 84 in Fig. 3 and so positioned that the disc rises when air is passing out of the cylinder and seats when the direction of air flow reverses. The rate of movement of the other two reciprocating elements, which may be the same in either direction, may be regulated by a needle valve or a fixed orifice interposed in one of the air conduits.

If an air supply for actuation of the pneumatic cylinders is not available from an outside source it may be provided by a small motor driven compressor, the capacity as to both volume and pressure varying with the size of the machine but being small in any case.

This apparatus may be provided with molds of any preferred arrangement, so long as they are open top and bottom, but the form illustrated in Figs. 10 and 11 is particularly adapted to this operation.

Referring to these figures, the outer frame 85, the partitions 86 and the cores 87 are formed of sheet steel and extend the full depth of the block. The cores are positioned by shallow bars 88 which produce only a groove in the upper face of the tile.

As an optional element, a steel strip 89 may be located at midlength, in the central bridge, providing a partial parting of the block of concrete which facilitates breaking it to form two tile of half length.

An additional optional element is a filler 90 which may be inserted at either or both ends of each mold to provide a channel for the placement of reinforcing steel to be grouted in place as the tile are assembled.

The apparatus above described may be operated at high speed without shock or heavy vibration, due to the use of pneumatic impulsion for the reciprocating elements and the provision of air cushions at each end of the actuating cylinders. The use of an elastic impulsion medium permits rapid acceleration and retardation of the reciprocating parts and permits their speeds to be accurately controlled. The mold block remains always in the upright position and the damage to freshly formed tile incurred in overturning molds is completely avoided. The tile, being ejected downwardly from the mold, are received on a resilient support which eliminates

all shock or jar, and are not handled until they have set sufficiently to be stacked. Hand labor is reduced to that required to keep the feed rack filled with empty pallets. In brief, the structure disclosed is materially more economical, as to first cost, maintenance and operation, than any similar apparatus of the prior art.

I claim as my invention:

1. Apparatus for producing concrete tile, comprising: a hopper for supplying a fluent concrete mixture; a mold block having bottomless openings of the form of the desired tile; a vibrating plate supported in fixed position beneath said hopper and spaced therefrom by a distance substantially equal to the depth of said mold block; a travelling plate attached to said mold block and level with the upper face thereof; means for periodically producing rapid minute vibrations in said vibrating plate; means for horizontally reciprocating said mold block and said travelling plate between a position at which said mold block is beneath said hopper and a position at which said travelling plate seals the lower end of said hopper; a plunger element having plungers adapted to enter and pass through the openings in said mold block to eject formed tile therefrom; means for producing vertical reciprocation of said plunger element; means for supporting a single pallet in a position beneath said plunger element; means for feeding single pallets onto said supporting means as said mold block returns to a position beneath said hopper; means for vertically reciprocating said supporting means between a position at which said single pallet is at least closely adjacent the lower face of said mold block and a position at which said pallet may be removed from said supporting means.

2. Structure as described in claim 1, in which said vibration producing means is electrically actuated.

3. Structure as described in claim 1, in which said reciprocating means are pneumatically actuated.

4. Structure as described in claim 1, in which said reciprocating means include double-acting pneumatic cylinders, a four-way valve affording communication between each said cylinder and a source of supply of compressed air, and cam means rotating in unison and actuating said valves to time said reciprocations in a desired order.

5. Structure as described in claim 1, including a continuously moving conveyor belt, and in which said pallet supporting means engages said pallet at opposite ends and passes below the upper surface of said belt prior to the end of its downward movement, thereby depositing said pallet on said belt to be removed from said supporting means.

WILLIAM M. BEYERSDORFER.
